US00D840395S

(12) **United States Design Patent** (10) Patent No.: **US D840,395 S**
(45) Date of Patent: **** Feb. 12, 2019**

(54) **HEAD-WORN COMPUTER**(71) Applicant: **Osterhout Group, Inc.**, San Francisco, CA (US)(72) Inventor: **Ralph F. Osterhout**, San Francisco, CA (US)(73) Assignee: **Osterhout Group, Inc.**, San Francisco, CA (US)(**) Term: **15 Years**(21) Appl. No.: **29/581,145**(22) Filed: **Oct. 17, 2016**(51) LOC (11) Cl. **14-02**

(52) U.S. Cl.

USPC ..... **D14/372**(58) **Field of Classification Search**USPC D14/372, 496, 432, 371, 125, 126, 129, D14/299; D16/300-342; 351/158, 153, 351/144; 345/7-9, 905; 455/344; 348/115, 53, 121, 739

(57) **CLAIM**

The ornamental design for a head-worn computer, as shown and described.

DESCRIPTION

FIG. 1 is a full view of a first embodiment of the new design; FIG. 2 is a top view of the first embodiment thereof; FIG. 3 is a front view of the first embodiment thereof; FIG. 4 is a side view of the first embodiment thereof; FIG. 5 is a full view of a second embodiment of the new design; FIG. 6 is a top view of the second embodiment thereof; FIG. 7 is a front view of the second embodiment thereof; and, FIG. 8 is a side view of the second embodiment thereof. The broken lines in FIGS. 1-8 are for environmental purposes only and form no part of the claimed design.
